PRECIPITATOR PURGE CIRCUIT

Roy Gordon Winklepleck, Roslyn Heights, N.Y., assignor to Apra Precipitator Corporation, New York, N.Y., a corporation of Delaware

Application September 10, 1957, Serial No. 683,113

3 Claims. (Cl. 183—7)

The present invention relates to a gas cleaning apparatus utilizing electrostatic precipitators and particularly to an improved system for purging or cleaning particles of solid material from the collecting surfaces of the precipitator.

The purging system of this invention is contemplated for use in connection with electrostatic precipitators of the type disclosed in the Karlsson Patent No. 2,582,133 issued January 8, 1952 in which the gas channels and the electrodes of the precipitator are arranged in sectors or banks each comprising a plurality of channels and electrodes and the precipitator is continuously cleaned by purging the banks in succession to remove collected particles. In the copending application of Hodson, No. 526,260—filed August 3, 1955, now Patent 2,835,337 dated May 20, 1958 there are disclosed a number of systems in which the collected particles are cleaned from the precipitator by a stream of purging gas that is caused to flow over the collecting surfaces and from which the collected particles are subsequently removed by directing the purge stream through "an aftercollector" or particle separator of the mechanical cyclone type. The present invention contemplates the employment of purge systems of this type in conjunction with several precipitators whose purge systems may be periodically employed together to effect a more intense cleaning of one of the precipitators.

Figure 1 is a schematic view illustrating the purge system of the present invention in connection with a pair of precipitators and wherein the purge systems of the several precipitators are periodically employed to effect cleaning of one of the precipitators; and

Figure 2 is a graph illustrating the operating conditions with respect to the pressure and volume produced by the cleaning fans; and

Figures 3 and 4 are views familiar to Figure 1 illustrating a system in which a single aftercollector and fan are employed for two precipitators.

In the drawings the numerals 10 and 20 designate a pair of electrostatic precipitators which are interposed in the gas ducts 11 and 21 for electrostatically removing entrained particles of solid material from the gas streams flowing through the ducts. As mentioned above, the particles deposited on the collecting surfaces of the precipitators 10 and 20 are periodically cleaned off by a stream of purging gas which is drawn over these surfaces by the purge fans 12 and 22. The precipitators 10 and 20 are connected by conduits 13 and 23 to mechanical collectors 14 and 24 which remove collected particles from the streams of purge gas as the latter are drawn through the collectors by the fans 12 and 22 via the ducts 15 and 25. As shown, the fans return the clean purge gas to the systems through ducts 16 and 26 connecting with the raw gas ducts 11 and 21, in which precollectors 17 and 27 are interposed at points in advance of the precipitators 10 and 20. A duct 30, containing a valve means 31 in the form of a damper, interconnects the conduits 13 and 23 downstream of dampers 32 and 34

2

in these conduits which connect with the related precipitators 10 and 20.

Normally each precipitator is cleaned continuously by its own purge system, the fan 12 acting through collector 14 on precipitator 10 while fan 22 purges collector 20. However, to improve efficiency the invention involves using the purge circuit or circuits normally cleaning two precipitators to clean one precipitator at approximately 20% increased purge velocity for a brief period 10 at predetermined intervals, say every 8 hours. This serves to reinstate the precipitator to a thoroughly clean condition in cases where normal purge velocity might be insufficient. The damper settings for normal and high purge are indicated below:

	"Purge"	"Damper"		
		31	32	34
20	Normal.....	Closed..	Open....	Open....
	High on 10.....	Open....	Open....	Closed..
	High on 20.....	Open....	Closed..	Open....

The reason a high purge results when two fans, in 25 parallel, are connected to one precipitator is illustrated in Fig. 2. This shows a typical fan curve "I," volume versus pressure and the system resistance curve "R." P_N is the normal operating point. When the two fans 12 and 22 are paralleled the combined fan curve "C," 30 shown in dotted lines, results. The intersection of R and the fan curve, point P_H , gives the operating point for high purge. The resulting purge volume in this case is 20% higher than with the normal damper setting.

Fig. 3 illustrates two electrostatic and mechanical collectors 10, 17 and 20, 27 with a common purge circuit containing aftercollector 44 and fan 42. The damper settings for normal and high purge are shown below:

	"Purge"	"Damper"	
		32	34
40	Normal.....	Open....	Open....
	High on 10.....	Open....	Closed..
	High on 20.....	Closed..	Open....

The reason a high purge can be obtained is shown in 45 Fig. 4. P_N is the resistance curve for two precipitators in parallel with both valves 32 and 34 open. R_H is for one precipitator in the purge circuit of fan 42. P_N is 50 the normal operating point of 50,000 c.f.m. total or 25,000 c.f.m. per precipitator. P_H is the high purge operating point of 30,000 c.f.m. total flow, but through only one precipitator, thereby giving a 20% increase in purge volume and velocity.

55 What I claim is:

1. A gas cleaning system comprising: a pair of electrostatic precipitators each acting to collect solid particles from a main gas stream flowing therethrough; fan means 60 associated with said precipitators for causing streams of purging gas to flow over their collecting surfaces to clean collected particles therefrom; a conduit connected to each precipitator for withdrawing streams of purging gas from each precipitator; collecting means for removing said solid particles from the purging gas streams; valve means 65 for each precipitator in the conduit connected thereto adapted when closed to cut off the flow of purging fluid through the precipitator; and a duct connected to said conduit downstream of said valve means placing each precipitator in communication with said collecting means functioning upon the closing of the valve means for either 70 precipitator to cause said fan means to act to purge only

the other precipitator and thereby increase the flow of purging gas therethrough.

2. A gas cleaning system comprising: a pair of electrostatic precipitators each acting to collect solid particles from a main gas stream flowing therethrough; an individual fan associated with each precipitator for causing a stream of purging gas to flow over the collecting surfaces of the precipitator for cleaning collected particles therefrom; a collector for each precipitator for removing said solid particles from its purging gas stream; conduits connecting each precipitator to the related collector; other conduits connecting the related fans to the collectors for drawing the streams of purging gas through either precipitator, its related collector and fan in series; valve means in each of said first mentioned conduits adapted when closed to temporarily cut off communication between the related precipitator and its collector and fan; a duct connecting said first mentioned conduits together at points between each precipitator and the collector related thereto downstream of said valves and acting to connect each precipitator to the collector related to the other precipitator; and valve means in said duct adapted when in open position to place both of the first mentioned conduits connecting with the precipitators in fluid communication with each other for connecting either precipitator to both collectors and their related fans increasing the flow of purging gas through one precipitator when the valve in the first mentioned conduit connected thereto is open and the valve in the first mentioned conduit connected to the other precipitator is closed so as to isolate it temporarily from its collector and fan.

3. A gas cleaning system comprising: a pair of electrostatic precipitators each acting to collect solid particles from a main gas stream flowing through the respective precipitator; an individual fan associated with each precipitator for causing a stream of purging gas to flow over the collecting surfaces of the precipitator to clean collected particles therefrom; a collector for each precipitator for removing said solid particles from its purging gas stream; conduits connecting each precipitator to the related collector; other conduits connecting the related fans to the collectors for drawing the streams of purging gas through either precipitator, its related collector and fan in series; a duct connecting said first mentioned conduits together at points between each precipitator and the collector related thereto and acting to connect each precipitator to the collector related to the other precipitator; valve means in said duct adapted when in open position to place both of said conduits in fluid communication with each other; and valve means in each of said first mentioned conduits connecting with said precipitators adapted when closed to cut off communication between either precipitator and its collector and fan and cause the related fan to act through said collector and said duct for purging the other precipitator, thereby increasing the flow of purging gas through said other precipitator.
